CLARENCE H. FORNEY, OF JERSEY CITY, NEW JERSEY, ASSIGNOR TO SONOCO PRODUCTS COMPANY, OF HARTSVILLE, SOUTH CAROLINA, A CORPORATION OF SOUTH CAROLINA

PAPER PACKING SPOOL

Application filed March 28, 1930. Serial No. 439,764.

This invention relates to paper spools, and has for an object to provide an improved construction wherein a comparatively strong structure is produced at a minimum expense.

6 Another object of the invention is to provide a paper spool wherein the minimum number of parts are used and yet the spool is formed with extra reinforcements at each end.

10 In the accompanying drawings—

Figure 1 is a side view of a paper spool disclosing an embodiment of the invention, part of the same being shown in section for better illustrating the construction;

15 Figure 2 is a sectional view taken from Figure 1 on the line 2—2;

Figure 3 is a view similar to the left hand end of Figure 1 but showing a modified form of the invention.

20 Referring to the accompanying drawings by numerals, 1 indicates the body or barrel of the spool, and 2 and 3 the ends. The thickness of these members and of the other members have been somewhat exaggerated in order to better illustrate the construction, but it will be understood that these members and the other parts may be made of any desired thickness and size without departing from the spirit of the invention.

25 The barrel 1 is preferably a complete tube and the ends 2 and 3 are separate discs held to the tube by a hollow rivet 4 which is associated with reinforcing and connecting sleeve 5. The sleeve 5 is formed from a section of

30 paper tubing and is bent into substantially the shape shown in Figure 1. This may be done by any well known means, and after it has been bent it is inserted as shown in Figure 1.

35 Before the insertion of sleeve 5 the interior of the barrel 1 is provided with a layer of glue 6 at each end, and then the tubular members 5 are inserted to substantially the

40 position shown in Figure 1.

45 Preferably in assembling the parts the sleeve 5 is first riveted to the end 2 or the end 3, as the case may be, and then the interior of the ends of the barrel supplied with glue or other adhesive. After this has been

done sleeve 5 with its end is slipped into position as shown in Figure 1.

Both ends may be placed in position at the same time, but preferably only one end at a time is inserted, and after it has been slipped into position the barrel 1 is set in vertical position with the end down, whereby the adhesive that has been pushed inwardly when sleeve 5 has been inserted will gradually gather and form a lump 7. This will stiffen and hold all the parts rigidly in place.

Also by this method, if there are any parts not supplied with glue, the extra supply 7 will gradually percolate to form a good connection substantially on all parts between the sleeve 5 and the barrel 1. After one end has been inserted and the glue dried, the other end is inserted and allowed to become dry.

50 After the spool has been thus completed it is ready for use, and by reason of the sleeve 5 the ends are strongly reinforced and consequently the spool as a whole is extra strong. Preferably all parts are made of paper with the exception of the rivet 4 and the glue 6.

55 In Figure 3 a modified form of the invention is shown, where all the parts are similar to that shown in Figure 1 except the sleeve 5' which is in the shape of a ball with diametrically opposite ends cut off, end 8 presenting a larger opening, while end 9 is clamped by the rivet 4'. This method of forming the sleeve 5' is such that the paper tube used may be more quickly pressed into shape and just as easily inserted.

60 In this form of sleeve there are no sharp turns and consequently none of the fibre of the sleeve is broken, which might be the case in sleeve 5 with the first structure unless some care was used in the formation of the sleeve. However, if this takes place it will not affect the usefulness of the spool as there is ample material to act as a connecting member and also as a brace.

65 After the parts have been assembled and the glue dried the spools are then ready for use or shipment.

What I claim is:

1. A spool consisting of a paper barrel, a pair of paper end disks, a sleeve of paper

at each end of said barrel fitting snugly therein, each of said sleeves having a turned-in end fitting flatwise against the end disk, a hollow eyelet extending through each of said turned-in ends and through the respective disks, each of said eyelets having a flange at each end for clamping the respective end disks to the respective turned-in ends of said sleeves and adhesive for securing the respective sleeves to said barrel.

2. A spool comprising a tubular barrel, a pair of end disks having perforations therein of less diameter than the internal diameter of said barrel, and means for securing each of said end disks to said barrel comprising a tubular sleeve snugly disposed within said barrel at the end thereof and adapted to extend from said end inwardly toward the intermediate portion of said barrel, an internal radial flange formed at the outer end of said sleeve, and adapted to fit flatwise against the inner surface of said end disk adjacent said perforation, the inner periphery of said flange defining an aperture coextensive with said perforation in said end disk, and a hollow eyelet extending through said aperture and said perforation, an outwardly extending radial flange formed on each end of said eyelet for clamping the end disk to the radial flange of said sleeve and means for rigidly securing said sleeves to said barrel.
